UNITED STATES PATENT OFFICE.

EARNEST BERTRAN SMITH, OF BUCKLIN, KANSAS.

ROTARY GAS-ENGINE.

1,086,095.

Specification of Letters Patent.

Patented Feb. 3, 1914.

Application filed January 8, 1913. Serial No. 740,839.

To all whom it may concern:

Be it known that I, EARNEST BERTRAN SMITH, a citizen of the United States, residing at Bucklin, in the county of Ford and 5 State of Kansas, have invented new and useful Improvements in Rotary Gas-Engines, of which the following is a specification.

This invention relates to rotary gas engines, the object in view being to provide a 10 rotary type of internal combustion motor, embodying, in connection with a suitable casing, a rotor working therein and provided with radially movable wings, wing operating blocks arranged at suitable points in the 15 casing and forming also the fixed walls of compression and expansion chambers, combined with a compression storage chamber, and means for delivering the compressed gas to said chamber, and again delivering 20 said gas under compression from the storage chamber to the expansion chamber, all controlled by the rotor and the parts carried thereby.

A further object of the invention is to 25 provide in connection with such an engine as that referred to, a novel form of governor, whereby the inflow of gas to the motor will be regulated by the compression, so that regularity in speed and torque of the rotor 30 may be regulated, and uniform operation of the motor maintained.

With the above and other objects in view, the invention consists in the construction, 35 combination and arrangement of parts, as will be hereinafter more fully described, illustrated in the accompanying drawings, and pointed out in the claim hereunto appended.

In the drawings: Figure 1 is a vertical 40 longitudinal section through a rotary gas engine, embodying the present invention. Fig. 2 is a substantially vertical diametrical section through the same. Fig. 3 is an inside elevation of a portion of one of the side 45 walls or heads of the casing, showing the form of the compressed gas inlet port. Fig. 4 is a side elevation of a portion of the rotor, showing one of the inlet ports therein.

The invention contemplated in this invention 50 comprises essentially an outer substantially cylindrical and stationary casing 1 provided with the oppositely arranged side walls or heads 2 and 3 provided centrally with bearing openings 4, through which 55 passes a rotary shaft 5 having fixedly mount-

ed thereon a cylindrical rotor 6 which revolves within the casing 1.

The rotor 6 is provided with a series of substantially radial pockets 7, in which is arranged a corresponding number of radially movable piston wings 8 normally pressed outwardly by means of springs 9 arranged in the spaces behind said wings, so that the outer extremities of said wings are caused to travel in contact with the inner 60 wall of the casing 1, as clearly shown in Fig. 1.

At diametrically opposite points within the casing, and preferably at the top and bottom thereof, are blocks 10 and 11. These 70 blocks are fixed within the casing, the outer faces thereof conforming to and fitting in close contact with the inner wall of the casing 1, while the inner faces of said blocks are concentrically milled, and bear, at 12, 75 against the periphery of the rotor. To prevent the passage of gas between the rotor and the blocks, the blocks are shown as provided with packing strips 13 which bear 80 against the periphery of the rotor. Each of the blocks 10 and 11 is also provided with inclined faces 14, against which the wings 8 ride, so that when they come into contact with said inclined faces, the piston wings are forced inwardly against the expansion 85 of the springs 9. At their opposite ends, the blocks 10 and 11 are provided with other inclined faces 15 which permit the wings to again move outwardly, until they rest and work in contact with the casing 1, all of 90 which will be readily seen in Fig. 1.

The block 10 is provided with a compression port 16 leading therethrough from the face 14 and extending also through the casing 1 and terminating in a nozzle 17 which 95 projects into a compression storage chamber 18 at the outside of the casing 1, the nozzle 17 being controlled by an outwardly moving check valve 19 which allows the compressed gas to pass into the chamber 18 but prevents the return of the same into the passage 16. The blocks 10 and 11 divide the space between the rotor 6 and casing 1 into a compression chamber 20 and an expansion chamber 21, and it will be noted that the end 100 walls of said chambers are formed by the blocks 10 and 11.

By reference to Fig. 2, it will be seen that from one side of the storage chamber 18, a by-pass 22 in the form of a pipe leads in- 105

wardly through the head or side wall 3 of the casing, where it terminates in an enlarged orifice 23 extending concentrically of the casing and rotor just within the plane 5 of the outer periphery of the rotor, as indicated by dotted lines in Fig. 1. This rotor is provided in rear of each wing 8 with an inlet port 24 which comes into registry with the orifice 23, and during the rotation of the 10 rotor remains in communication with the by-pass 22 long enough to admit a full charge of compressed gas into the compression chamber 21 between the fixed wall 15 of the upper block and the adjacent and receiving 15 wing 8. When the wing 8 has proceeded a sufficient distance from the wall 15 to admit the full charge of compressed gas from the chamber 18, the ports 23 and 24 pass out of registry with each other, thereby cutting off 20 the by-pass 22, and immediately thereafter the gas is ignited. The exhaust gas is forced along the expansion chamber 21 by the next following wing 8, and is conducted through the exhaust port 26 in the bottom block 11. 25

27 designates the primary intake port which leads into the compression chamber 20, 30 and which has in communication therewith a carbureter 28, to the butterfly stem of which is attached a governor rod 29 leading upwardly into an extension 30 of the compression storage chamber 18, where said rod is 35 connected to a valve 31 influenced by the pressure in the chamber 18, in such manner that when the pressure becomes greater than the predetermined degree, the valve 31 will be pressed downwardly, so as to operate on 40 the rod 29 and partially throttle the carbureter, so as to diminish the flow of explosive mixture delivered therefrom to the engine.

In order to prevent the passage of gas 45 between the side walls of the rotor and the heads 2 and 3 of the engine, the rotor is provided at opposite sides with projecting concentric packing rings 32 which are received in grooves 33 formed in the inner faces of 50 the walls 2 and 3 of the casing. Each of the wings 8 is also shown as provided at its outer edge with a spring pressed packing strip 34, and with other spring pressed packing strips 35 at the opposite sides 55 thereof, said strips being for the purpose of maintaining close contact between the wings and the casing to prevent the passage of gas past the same.

The operation of the engine is as follows: 60 The gas is admitted through the intake 27 into the compression chamber 20, around which it is swept by the following wing, compressed and forced through the passage

16 into the compression storage chamber 18 which has a much smaller capacity than that 65 of the compression chamber 20. The gas is thus trapped under compression by the check valve 19 in the chamber 18, where it remains until the next port 24 of the rotor registers with the concentrically enlarged 70 inner end or orifice 23 of the by-pass 22. Thereupon the compressed gas flows quickly from the chamber 18 into the expansion chamber 21 between the fixed wall 15 of the upper block and the adjacent and receiving 75 wing 8. When the wing 8 has proceeded a sufficient distance from the wall 15 to admit the full charge of compressed gas from the chamber 18, the ports 23 and 24 pass out of registry with each other, thereby cutting off 80 the by-pass 22, and immediately thereafter the gas is ignited. The exhaust gas is forced along the expansion chamber 21 by the next following wing 8, and is conducted through the exhaust port 26 in the bottom block 11. 85

It will be observed from the foregoing that a perfectly fresh charge of compressed gas is admitted behind each wing of the rotor, and the exhaust or burnt gases are thoroughly scavenged from the expansion 90 chamber 21, so that there can be no admixture of the fresh and burnt gases, thereby adding materially to the efficiency and power of the engine.

What is claimed is:

In a rotary gas engine, a cylindrical casing, a rotor therein, radial outwardly spring pressed wings carried by the rotor and working in contact with the casing, diametrically opposite blocks in the casing having inclined faces which control the inward and outward movements of the wings and also form fixed walls of the expansion and compression chambers, one of said blocks being provided with a compression port and the 100 other with an exhaust port, a compression storage chamber in receiving communication with said compression port, a by-pass leading from said storage chamber to the expansion chamber, means controlled by the 105 rotor for opening up and cutting off communication between the storage and expansion chambers, a valve controlling the communication between the carbureter and compression chamber and operated by pressure 110 operated means in the storage chamber, and a connection between said pressure operated valve and carbureter, said valve acting as a governor for controlling the admission of 115 gas from the carbureter to the engine. 120

In testimony whereof I affix my signature in presence of two witnesses.

EARNEST BERTRAN SMITH.
